UNITED STATES PATENT OFFICE.

ROLF THELEN, OF MADISON, WISCONSIN, DEDICATED, BY MESNE ASSIGNMENTS, TO
THE CITIZENS OF THE UNITED STATES OF AMERICA.

REVERSIBLE-CIRCULATION INTERNAL-FAN KILN.

Application filed July 12, 1923. Serial No. 651,071.

(FILED UNDER THE ACT OF MARCH 3, 1883, 22 STAT. L., 625.)

To all whom it may concern:

Be it known that I, ROLF THELEN, a citizen of the United States of America, and an employee of the Department of Agriculture, residing in Madison, Wisconsin (whose post-office address is Madison, Wisconsin), have invented a new and Improved Reversible-Circulation Internal-Fan Kiln.

This application is made under the act of
10 March 3, 1883, chapter 143 (22 Stat. 625),
and the invention herein described and
claimed may be used by the Government of
the United States, its officers and employees,
and by any person in the United States
15 without the payment to me of any royalty
thereon. I hereby dedicate the same to the
free use of the Government and the people
of the United States.

My invention consists in an improvement
20 in the design of forced circulation kilns or
chambers for drying and conditioning lumber or similar material. However, its use is
not limited to wood or wood products. It
consists in the adaptation of fans of the disk
25 type, or similar types, to the production of
a unique internal circulation of air and the
vapor in the kiln combined with the produc-
tion and regulation of the heat and the
humidity within the kiln.

30 This invention is illustrated in Figures
1 and 2. Figure 1 represents a longitudinal
vertical section, and Figure 2 represents a
transverse vertical section.

The principal feature which I claim as
35 novel and an improvement over existing
kilns is the use and arrangement of the
fans and the air distributing system. This
arrangement is such that a very fast and
uniform circulation of air and vapor
40 through the pile of lumber may be secured,
and permits the periodic reversal of the di-
rection of the air movement by simply re-
versing the direction of rotation of the fans.
The air distributing system provides a very
45 uniform flow of air throughout the length
of the kiln and eliminates the non-uniform-
ity of drying, which is one of the commonest
troubles experienced in the ordinary kiln.
The arrangement of the fans upon a single
50 shaft extending throughout the length of
the kiln provides a simple means of produc-
ing a brisk circulation; and the elimination
of comparatively small ducts such as those

used in external blower kilns reduces very
materially the work required to produce a
given circulation. The differences in air
pressure required in the operation of this
kiln are much smaller than those ordinarily
required in kilns employing centrifugal
blowers, and the disk fans operate very ef-
ficiently at these low pressures. It is pos-
sible, therefore, by the use of this invention
to produce a very great and uniform circu-
lation of air and vapor within the kiln with
a very small expenditure of power.

While it is obvious that there are many
possible ways in which the use of internal
fans can be adapted to drying kilns of dif-
ferent types, this invention is limited to
kilns in which the lumber is flat cross piled
and in which a single row of fans is em-
ployed. It is further limited in that ad-
jacent fans are of opposite pitch.

Any well-known means of heating the air
and the vapor in the kiln may be used in
conjunction with this invention. When
steam pipes are used they may be arranged
beneath the lumber piles or in any other
convenient manner. Any convenient form
and arrangement of heaters may be used.

The drawings show and the specification
describes steam jet pipes for increasing the
humidity, and air inlet flues with suitable
dampers for decreasing the humidity.

While the drawings show and the speci-
fication describes specific means for heating
the air and the vapor in the kiln and for
regulating the humidity of the air in the
kiln, this invention is not limited specif-
ically to the arrangements described, but
may make use of any other suitable and
well-known means for accomplishing the
same purposes. While the drawings illus-
trate and the specification describes a spe-
cific form of flat cross piled lumber, the in-
vention is not limited to this particular
form since it is equally applicable to all
other forms of flat cross piling and to other
well-known methods of arranging the lum-
ber on the trucks.

Referring to Figures 1 and 2 which are
correspondingly lettered: AA and YY are
air chambers in the lower portion of the
kiln. When the direction of air circulation
is as indicated by the arrows, air chambers
AA are under a slight pressure, being in

the nature of plenum chambers, and the air chambers YY are under a slight vacuum, being in the nature of vacuum chambers. When the direction of circulation is reversed, air chambers AA become vacuum chambers and air chambers YY become plenum chambers. BB are the fans producing the circulation. Straight-bladed disk fans are preferable. Any type of fan, however, in which the reversal of the direction of rotation of the fan produces a reversal in the direction of the flow of air current passing through the fan can be used. Adjacent fans are of opposite pitch so that they blow toward each other when the rotation is in one direction and away from each other when it is in the opposite direction. Figure 1 shows the fan farthest to the left to be right-handed and the one next to it left-handed. The third and fifth fans from the left are also right-handed, and the second, fourth, and sixth left-handed. When the flow of air is as indicated in Figure 1 all of the fans blow into the respective air chambers A, drawing air from the respective air chambers Y. When the direction of rotation of the fans is reversed, the fans will all blow into the respective air chambers Y, drawing from the respective air chambers A. C is the shaft upon which the fans are mounted. Provision is made to take care of the expansion and contraction of this shaft with changes in temperature in the kiln. DD are air inlet dampers used to regulate and to control the amount of air entering the kilns from the outside. EE are the heating coils. The coils illustrated in the drawings and described in the specification are of the header type. This invention is not, however, limited to this type since any common or well known type may be adapted to it. FF are the steam jet pipes used to increase the humidity of the air in the kiln. Those in the air chambers AA may be used when the direction of flow of the air current is as indicated in Figure 1. When the direction of flow is reversed, those jet pipes in air chambers YY may be used. GG are the lumber supporting trucks. HH are the shaft hangers. II are bearings for the shaft C. JJ are the tracks upon which the lumber-supporting trucks run. The invention is not specifically limited to the form and arrangement of lumber-supporting trucks, tracks, and track supports illustrated since any well-known method of supporting the lumber may be used without influencing in any way the efficiency or operation of the kiln. KK are the walls of the drying chamber. LL is the lumber to be dried. MM are track supports. N is the shaft pulley. OO are air outlet dampers for controlling the amount of air being exhausted from the kiln. P is a belt passing over the pulleys N and Q. Q is the motor pulley. R is the motor which furnishes the power to drive the fans. S is a switch for controlling the speed and direction of the rotation of the motor armature. While the drawings show and the specification describes an electric motor, any other suitable driving means may be used. TT are air outlet flues in which the dampers OO are fitted. VV are the air chamber partitions. These partitions extend across the kiln from side wall to side wall and serve to separate air chambers AA from air chambers YY. Suitable housings or openings are provided in these air chamber partitions for the fans BB. WW and XX are air passages adjacent to and between the lumber on the lumber-supporting trucks. While the drawings illustrate and the specification describes parallel-sided air passages, air passages of other common and well-known shapes may be used. ZZ are diffusers, the purpose of which is to permit a uniform flow of air into and out of the air chambers AA and YY. Except for unavoidable leakages, these diffusers form the only passage between the air chambers and the air passages.

The operation of the kiln is briefly as follows: The lumber is placed in the kiln, the doors and all of the dampers are closed, and the kiln is started. Steam is turned into the coils and one set of steam jets is turned on. Suitable regulating devices are provided to control and regulate the supply of steam to the heating coils and the supply of steam to the steam jets. If it is found impossible to reduce the humidity to the desired point with the steam jets all turned off, the dampers DD and OO are opened to allow fresh air to enter and moist air to escape. These dampers are adjusted so that a humidity below that desired will be secured. The steam jets may then automatically supply a sufficient amount of steam to bring the humidity up to the desired point. If the direction of the rotation of the motor, the shaft, and the fans is such as to cause the air flow to be as indicated in Figure 1, the air and vapor will pass upwardly out of the air chambers AA, through the diffusers ZZ, into the air passages XX, thence laterally through LL, the piles of lumber to be dried, into the air passages WW, downward through these passages, and through the diffusers ZZ in the tops of the air chambers YY, through these air chambers into the fans BB, and thence into the air chambers AA. The resistance to the flow of air caused by the diffusers ZZ assists in maintaining a slight plenum in the air chambers AA and producing a uniform distribution of the air through the air passages XX. While the drawings illustrate and the specification de-

scribes a single set of diffusers for each air chamber, two or more sets of any well-known form may be used for each air chamber if greater uniformity of air distribution be desired. The location of the fans BB and the fact that adjacent fans blow in opposite directions tends to eliminate in large measure the lack of uniformity in air distribution resulting from the velocity of the air issuing 10 from the fans.

It is well understood that when the circulation of the air in the kiln is continuously in one direction, that portion of the pile at which the air enters will dry more rapidly 15 than the opposite side since the air in its passage through the lumber picks up moisture and thus reduces its drying capacity. To overcome this defect, the direction of rotation of the fans may be reversed, thus 20 reversing the direction of the motion of the air through the lumber piles. This may be done periodically every two or three days or oftener, the exact period being determined by the condition of the lumber in the kiln. 25 The direction of the air travel is then as follows: The air passes from the air chambers YY upward through the diffusers ZZ at the tops of these air chambers into the air 30 passages WW, from these laterally through LL, the lumber to be dried, into the air passages XX, downward through these air passages through the diffusers ZZ, on top of the air chambers AA, into the air chambers AA, thence through the fans BB into the air 35 chambers YY.

Having fully described the principles of this invention and the manner in which they can be embodied in a dry kiln, I claim as original:

40 1. In a dry kiln arranged for flatwise cross piling: a series of fans in which adjacent fans are of opposite pitch; a shaft on which the fans are mounted for rotation; and means for rotating said shaft in either direction to cause reversal of the circulation of the air and vapor in said kiln.

50 2. In a dry kiln arranged for flatwise cross piling: a series of fans in which adjacent fans are of opposite pitch; a shaft on which the fans are mounted for rotation; means for rotating said shaft in either direction to cause reversal of the circulation of the air and vapor in said kiln; and an air 55 distributing system comprising air chambers and diffusers.

60 3. In a dry kiln arranged for flatwise cross piling: a series of fans in which adjacent fans are of opposite pitch; a shaft on which the fans are mounted for rotation; means for rotating said shaft in either direction to cause reversal of the circulation 65 of the air and vapor in said kiln; an air distributing system comprising air chambers and diffusers; and dampered air inlet flues and dampered air outlet flues.

4. In a dry kiln arranged for flatwise cross piling: a series of fans in which adjacent fans are of opposite pitch; a shaft on which the fans are mounted for rotation; means for rotating said shaft in either direction to cause reversal of the circulation 70 of the air and vapor in said kiln; an air distributing system comprising air chambers and diffusers; dampered air inlet flues and dampered air outlet flues; and means for heating the kiln and its contents. 75

5. In a dry kiln arranged for flatwise cross piling: a series of fans in which adjacent fans are of opposite pitch; a shaft on which the fans are mounted for rotation; means for rotating said shaft in either direction to cause reversal of the circulation 80 of the air and vapor in said kiln; an air distributing system comprising air chambers and diffusers; dampered air inlet flues and dampered air outlet flues; means for heating the kiln and its contents; and means for humidifying the atmosphere in the kiln. 85

6. In a dry kiln arranged for flatwise cross piling: two series of air chambers, the 90 chambers of one series alternating with those of the other series.

7. In a dry kiln arranged for flatwise cross piling: an air distributing system comprising two series of air chambers, the chambers of one series alternating with those of the other series, and diffusers. 95

8. In a dry kiln arranged for flatwise cross piling: an air distributing system comprising two series of air chambers, the chambers of one series alternating with those of the other series, and diffusers; and means for producing a slight vacuum in one series of air chambers simultaneously with a slight plenum in the other series of air chambers. 100

9. In a dry kiln arranged for flatwise cross piling: an air distributing system comprising two series of air chambers, the chambers of one series alternating with those of the other series, and diffusers; and means for producing a slight vacuum in either series of air chambers simultaneously with a slight plenum in the other series of air chambers. 110

10. In a dry kiln arranged for flatwise cross piling: an air distributing system comprising two series of air chambers, the chambers of one series alternating with those of the other series, and diffusers; means for producing a slight vacuum in one series of air chambers simultaneously with a slight plenum in the other series of air chambers; and dampered air inlet flues and dampered air outlet flues. 115

11. In a dry kiln arranged for flatwise cross piling: an air distributing system comprising two series of air chambers, the chambers of one series alternating with those of the other series, and diffusers; means for producing a slight vacuum in either series of air chambers simultaneously with a slight 125 plenum in the other series of air chambers.

- 4
- plenum in the other series of air chambers; and dampered air inlet flues and dampered air outlet flues.
12. In a dry kiln arranged for flatwise cross piling: an air distributing system comprising two series of air chambers, the chambers of one series alternating with those of the other series, and diffusers; means for producing a slight vacuum in one series of air chambers simultaneously with a slight plenum in the other series of air chambers; dampered air inlet flues and dampered air outlet flues; and means for heating the kiln and its contents.
13. In a dry kiln arranged for flatwise cross piling: an air distributing system comprising two series of air chambers, the chambers of one series alternating with those of the other series, and diffusers; means for producing a slight vacuum in either series of air chambers simultaneously with a slight plenum in the other series of air chambers; dampered air inlet flues and dampered air outlet flues; and means for heating the kiln and its contents.
14. In a dry kiln arranged for flatwise cross piling: an air distributing system comprising two series of air chambers, the chambers of one series alternating with those of the other series, and diffusers; means for producing a slight vacuum in one series of air chambers simultaneously with a slight plenum in the other series of air chambers; dampered air inlet flues and dampered air outlet flues; means for heating the kiln and its contents; and means for humidifying the atmosphere in the kiln.
15. In a dry kiln arranged for flatwise cross piling: an air distributing system comprising two series of air chambers, the chambers of one series alternating with those of the other series, and diffusers; means for producing a slight vacuum in either series of air chambers simultaneously with a slight plenum in the other series of air chambers; dampered air inlet flues and dampered air outlet flues; means for heating the kiln and its contents; and means for humidifying the atmosphere in the kiln.

ROLF THELEN.
